(57) **CLAIM**

The ornamental design for a valve head, as shown and described.

DESCRIPTION

FIG. 1 is a perspective front view of a valve head;

FIG. 2 is a front elevation view thereof;

FIG. 3 is a rear elevation view thereof;

FIG. 4 is a left side elevation view thereof; the right side view being a mirror image thereof;

FIG. 5 is a top plan view thereof; and,

FIG. 6 is a bottom plan view thereof.

The broken line showing in the drawings is for the purpose of illustrating portions of the valve head and forms no part of the claimed design.
